COATING MACHINE AND METHOD OF COATING

Glenn L. Sherwood, Benton Harbor, Mich., assignor to Kaywood Corporation, Benton Harbor, Mich., a corporation of Michigan

Application July 24, 1940, Serial No. 347,135

11 Claims. (Cl. 117—115)

1

This invention relates to coating machinery and more particularly to machinery of this kind for coating a strip or ribbon of material, such as metal, for use afterward in the construction or manufacture of any desired structure or article of commerce.

Generally stated, the object of the invention is to provide an improved machine and an improved method for use in the manufacture of Venetian blinds or similar things, and to provide a machine and method for this purpose that will substantially or materially reduce the cost of production of the Venetian blinds or other things, by simplifying and expediting the coating of the slats from which the blinds or other things are made.

More specifically considered, the object of the invention is to provide an improved machine and method for coating a strip or ribbon of cold rolled steel with enamel or similar material, or with paint of any desired character, in such a manner that the enamel or other liquid material will dry smoothly and effectively on the surface of the steel strip or ribbon, so that the latter may then be cut into lengths suitable for use as the slats or Venetian blinds or other things.

It is also an object to provide certain novel details and features of construction and combinations tending to increase the general efficiency and desirability of an apparatus and method of this particular character.

To the foregoing and other useful ends, the invention consists in matters hereinafter set forth and claimed and shown in the accompanying drawings, in which—

Fig. 1 is a side elevation of a machine or apparatus embodying the principles of the invention, showing certain portions thereof broken away for convenience of illustration.

Fig. 2 is a rear elevation of the structure shown in Fig. 1 of the drawings.

Fig. 3 is a vertical sectional view on line 3—3 in Fig. 2 of the drawings, on a larger scale.

Fig. 4 is a vertical section of a portion of the apparatus on line 4—4 in Fig. 3 of the drawings.

Fig. 5 is an enlarged sectional view on line 5—5 in Fig. 2 of the drawings.

Fig. 6 is a perspective of the two portions of the device shown in Fig. 5 of the drawings.

Fig. 7 is an enlarged horizontal section on line 7—7 in Fig. 5 of the drawings.

Fig. 8 is a vertical section on line 8—8 in Fig. 7 of the drawings.

Fig. 9 is a perspective of the reels or spools upon which the coated strips or ribbons of steel

are wound as they come from the drying oven of the said machine or apparatus.

Fig. 10 is a vertical fragmentary section on line 10—10 in Fig. 2 of the drawings.

As thus illustrated, a plurality of reels 1 is mounted on a single horizontal shaft 2, the ends of which latter rotate in bearings 3 of any suitable character. The thin steel strips or ribbons 4 are carried on these reels and are pulled downwardly from said reels through the enamel or paint 5 in the container 6 and around the idlers 7 and then upwardly through the drying or baking oven 8, which latter is disposed vertically in a vertical transverse plane and is of sufficient height to insure the desired drying or baking of the enamel or paint on the strips. The coated and partially dried strips then move over the idlers 9 mounted at the top of the machine or apparatus and are then pulled downwardly around the idler 10 and then vertically downward in the oven 8 until they travel around the driving roll 11 on the horizontal shaft 12, which latter is the main driving shaft of the machine. By looking at Figs. 1 and 3, it will be seen that the downwardly moving coated portions of the strips move outside of the oven 8 for a distance before engaging the driving rolls 11, and the coated strips then pass under the rolls 11 and are wound on a multiple spool rotating about an axis 13 which rotates about a horizontal axis and is driven from the shaft 12 previously mentioned, so that in this way the strips are pulled through the machine or apparatus and are then individually wound tight in the circumferential grooves or spaces of the spool, as indicated more clearly in Figs. 9 and 10 of the drawings.

That is the general plan of the apparatus and method employed, and the best results are obtained, it is found, when the oven heat is maintained at a temperature anywhere from two hundred and seventy to three hundred degrees Fahrenheit, so that the strips or ribbons remain approximately one-half an hour in the oven. There is approximately eight hundred feet of strip or ribbon on the reel 4, preferably, and it preferably requires about eight hours to run a reel of the cold rolled sheet steel through the machine, so that it will finally emerge very smoothly and very satisfactorily coated with the enamel or paint or any other liquid material. Preferably, of course, so that a plurality of strips or ribbons can be run through the machine at the same time, and coated in different colors, there are as many containers 6 as there are strips to be coated, with a different color of paint or

enamel in each container. These enamel containers are set in a water tank 14, and the water is preferably maintained at a temperature of about one hundred and twenty degrees, so that the paint or enamel will have that temperature while the strips or ribbons are passing through.

After the strips or ribbons come off the reel 1, they pass through a brake device comprising rolls 15 driven at a lower rate of speed than the tape or ribbon is moving, and the strips or ribbons are held against these rolls by the felt brake device 16 which is controlled by the tension spring or springs 17, and at this juncture it will also be observed that the reel 1 is governed by a band brake 18 which is under the tension of the spring or springs 19, shown in Fig. 3 of the drawings.

Everything is preferably driven from the shaft 12 previously described, in the manner indicated in Fig. 1 of the drawings, and this shaft is preferably driven by an electric motor 20 through a reducing gear 21 of any suitable character, whereby the said driven elements of the machine will each be given the predetermined speed necessary or desirable for doing the work in the required manner.

Rolls 22 under the control of the springs 23 press the coated and dried ribbons against the under sides of the roll 11, as shown in Fig. 3 of the drawings, and while this is sufficient to pull the tapes or ribbons through the machine, it will be seen that the spool or reel 13 is also driven by the roller 24 which is belt-driven from the shaft 12 previously mentioned.

A heater 25, of any suitable character, is provided to furnish heated air to the oven, and this is preferably accomplished by using a vertical air-jacket 26 around the smoke-pipe 27, which latter may carry off the products of combustion from the heater, assuming that oil or gas or fuel of some kind is burned in the said heater to provide the required heat. The heated air in the jacket 26 is discharged through pipes 28 into the upper portion of the heater, and the motor-driven fan 29 then sucks the heated air downwardly and through the pipe 30, where it is then discharged back into the said heater. Of course, some fresh air enters the bottom of the heater at 31 to compensate for losses.

Thus, looking at Fig. 1 of the drawings, it will be seen that the coated tape or ribbons travel a distance in the atmosphere outside of the oven, after leaving the rollers 9, and then travel downwardly inside of the heater, and then outside of the latter before reaching the driven rollers 11, for it is found that in this way the enamel or paint or other material is more satisfactorily dried and hardened.

Paint is supplied to the different containers 6 in any suitable or desired manner, as by simply pouring it in by hand, and each container is preferably provided with a baffle 32 to prevent the rippled from reaching the strips or ribbons of metal or other suitable material.

Preferably, the multiple spool may be lifted out when it becomes entirely loaded with the coated strips or ribbons of metal, so that the said strips may then be removed and cut into sections of desired length for Venetian blind slats, or for other purposes.

In actual practice, of course, it becomes desirable to keep the tape or ribbons from vibrating as they emerge and rise out of the paint or enamel in the containers. This can be done in any suitable or desired manner, as for example, by providing a couple of plates 34 and 35, be-

tween which the tape or ribbon moves upwardly, it being observed that the plate 34 is fastened to the side walls of the paint or enamel container. The plate 35 is subject to the action of the spring or springs 36, through the medium of levers 37, so that the flat strip of metal is momentarily made trough-shaped, as shown at 38 in Fig. 7 of the drawings. In other words, it becomes partially tubular, and anything tubular, or partially so, is much stiffer and more rigid than a sheet or strip of metal in perfectly flat form. In other words, the plate 34 is concave, and the plate 35 is convex, in horizontal cross-section, and this means that the strip or ribbon becomes momentarily shaped like a shallow trough in cross-section, and in that way it gains rigidity enough to prevent vibration thereof.

Moving at a comparatively slow rate of speed, the ascending portions of the tape or ribbons are, in effect, wiped and freed of surplus paint or enamel at the surface of the body of liquid in each container. In this way, there is no downward flow of the enamel or paint on the ascending portions of the ribbons, and the liquid is dried and baked in very smooth condition on each ribbon.

It has been found that when the tape or ribbons move about eighteen inches a minute, good results have been obtained, and good results have been obtained with cold rolled steel two inches wide and about eight-one-thousandths of an inch in thickness. Each strip or ribbon is about one minute in the paint bath, preferably, although this would probably change or vary for different kinds of enamel or paint or other liquid, and the same is true of the time required in the drying and baking oven. The proportions and the general height of the machine or apparatus should be, therefore, such as to insure the above figures.

With the apparatus and method as shown and described, the coating of the tape or ribbon is such that they can be permanently pressed into trough-shape, to make them rigid, as in the case of slats for Venetian blinds, and while the metal is thin and comparatively light, the slats for blinds made in this way are surprisingly strong and rigid. The forming of the strips or ribbons of metal in this way, by converting each one into a shallow trough, is done without correcting or in any way damaging the dried, baked enamel or paint thereon. It thus becomes possible to make the coating step of the process a practically continuous one, as the coating is done on relatively long strips instead of on short ones.

Obviously, there is considerable room or latitude for changes in the construction of the apparatus shown and described, without going outside the scope and spirit of the invention. For example, long rollers might be used as a substitute for some of the sets of individual rollers. Preferably, the apparatus is substantially or practically vertical, so that the tape or ribbons travel upwardly and then downwardly. This makes for a practically minimum amount of floor space necessary for the machine or apparatus, but it is conceivable that the tape or ribbons could be made to travel horizontally instead of vertically, by using a different relative arrangement of the elements of the machine or apparatus.

An important thing to observe is that while the coating is done by a dipping process, it is true that the motion of the article or thing being dipped is never reversed in the paint bath, as it travels through the latter by continuous motion

and without any interruption or reversal thereof.

Thus the object to be coated travels continuously in one direction and it rises so slowly out of the paint or enamel bath, that the liquid is spread evenly and uniformly in a thin film over the surfaces of the metal or other material, and this film of liquid is not disturbed by any jolting or jarring or vibration of the strip or ribbon of metal, with the result that when the coated tape or strip is finally wound on the reel 33, the film of enamel or paint is perfectly smooth and uniform in thickness, and completely dry. Things of this kind can be coated by spraying the paint or enamel on them, but there are many difficulties and objections involved in spraying which are completely eliminated or obviated by a dipping process of the kind shown and described. For example, spraying of narrow or small articles or objects is usually accompanied by a serious waste of the liquid material, whereas with the dipping process shown and described, there is absolutely no waste of the paint or enamel. In addition, spraying involves the atomizing of the liquid, and if the latter contains a drier of one kind or another, the fine particles of the liquid may become too hard before they strike the surface of the article to be coated. With the multiple reels shown and described, the plurality of strips or ribbons can be coated simultaneously, each with a different color or shade, and this is possible without increasing the height of the machine. The tape or ribbon is kept taut and held against distortion, with the one exception that it is momentarily curved in cross section immediately before it emerges from the surface of the liquid, and this slight momentary distortion tends to prevent vibration of the strip or ribbon, which is desirable inasmuch as vibration might disturb the film of liquid on the ribbon. But with the latter held against any vibration, the film is of uniform thickness and is absolutely stable, so that it dries or bakes in a perfectly smooth condition and with a glossy surface that is entirely free from roughness or unevenness. Therefore, if the strip or ribbon is run at too high a speed, it will carry up an excess of liquid that will then run back down and streak the surface of the film. But when the ribbon is run at such a slow rate of speed that it carries upward no excess liquid, a thin film is insured of uniform thickness and with no unevenness of the surface thereof.

It will be observed that while the strip or ribbon with the film of paint or enamel thereon is moving in one direction, the heated air is moving in the opposite direction, inasmuch as the said tape or ribbon moves upwardly in the oven 8, while the heated air in the latter moves downwardly. In this way, any given spot on the strip or ribbon is subjected to steady and changing supply of heated air, during its course of travel through the oven. In this way, the strip or ribbon encounters the minimum temperature when it enters the lower end of the oven, and then encounters the maximum temperature when it enters the upper portion of the oven. This, of course, means the upwardly traveling portion of the tape or ribbon, for while the latter ultimately passes outside of the oven and through the ordinary atmosphere, and then downwardly a distance within the oven, it will be seen that the greater course or distance of travel is upwardly within the oven.

If the several strips or ribbons are being coated to become the slats of Venetian blinds, it is obvious that a suitable or desired means can be

used for curving the dry-coated material transversely, so that it is slightly trough-shaped in cross section, and that any suitable means can be employed for cutting the strips into lengths suitable for the Venetian blinds, and that this cutting operation can be performed before or even after the strip or ribbon is permanently curved in cross section.

Thus, the dipping process for coating the sheet steel or other suitable material becomes continuous, in effect, instead of being intermittent as it would be if the material was cut into suitable lengths and thereafter dipped and coated. The enamel, paint or other liquid material employed should be of any well known kind that is tough and pliable, when dried, so that the forming of the strips will not crack or injure the coating thereon.

The foregoing is a description of the apparatus in what might be called its simplest form, assuming that the strips or ribbons are all moving simultaneously, from supply reels that are all on one shaft, and finally to storage reels that are all on another shaft.

25 However, in actual practice, it is found preferable to have the supply reels operating separately and independently of each other, and to have the storage reels upon which the coated strips or ribbons are wound also operating separately and
30 independently of each other, whereby the amount of wind or coiled-up strip or ribbon may be considerably different on the different reels or drums, or on the spools as they may be called.

For that purpose, there are then as many supply reels 11 as there are strips or ribbons, or as there are paint or enamel containers for holding the liquid. Also, for that purpose, there are as many storage reels or drums 33 as there are strips or ribbons, or as there are liquid containers.

40 That means that there are as many band brakes
18 as there are supply reels or drums on the axis
2. The separate and independent storage reels
33 practically float on the roller 24 and the roller
39, which latter is merely an idler, the roller 24
45 being driven at a higher speed than the feed, in

order to keep the strips or ribbons taut on the reels 33, and this compensates for the difference in speed of the tape or ribbon when it begins to wind up on a reel, and its speed when the reel is nearly full. As shown more clearly in Fig. 9, the framing 40 has some transverse channel irons 41 and 42 thereon, provided with pins 43 that keep the reels 33 properly separated and upright on the rolls 24 and 39. In this way, the supply

55 reels and the storage reels can be used in different ways, and one reel can be running a small job while another reel is running a large job, and other things can be done, quite obviously, that could not be done if all the supply reels were
60 rigid with each other, and if all the storage reels were rigid with each other. Of course, the speed of all the strips or ribbons is maintained at a certain predetermined degree by the fixed speed of the roll 11, and its idler roll 22, which are maintained at a predetermined given speed in order to insure the proper timing of the apparatus, not only as to the timing of the strips or ribbons in the bath, but also in the oven. Obviously, there
65 must be no disturbance that would cause ripple
70 in the bath, and the length of time that the strips or ribbons are in the oven, or being dried and hardened, must be predetermined to insure the proper drying and hardening of the thin film of liquid material on the strips or ribbons. It
75 will also be seen that there are preferably as many

springs 23, and spring-pressed rollers 22, as there are ribbons or strips to be coated, for it is better to have the feeding grip individual for each strip or ribbon, for in that way there is compensation for any difference in thickness as between the strips or ribbons, and the machine may be working simultaneously on both relatively thick and relatively thin strips or ribbons, and at this juncture it is to be observed that there are as many friction brakes 16 as there are rolls 15, in the preferred form of the apparatus.

Of course, the timing and temperatures mentioned are merely those that have been found to be proper for a particular enamel which has been used for coating the strips. Of course, some enamel is baked at a temperature as high as six hundred degrees Fahrenheit, and all the other conditions depend more or less on the type of material used, for some enamels or paints dry and bake quickly while others require more time, and hence the distance of travel and the temperature of the elements and other factors of that kind will vary according to the type of material used. The invention, therefore, is not limited to any particular temperature or timing or length of travel, as that will vary more or less in accordance with different conditions.

What I claim as my invention:

1. An apparatus for continuously coating a metal ribbon with a liquid coating composition which comprises a container for the liquid coating composition, the largest dimension of which container is many times smaller than the length of the metal ribbon, means for continuously guiding the metal ribbon into and out of the liquid in the container at a slow even speed whereby to uniformly coat the metal ribbon with a thin smooth film of the coating composition and means for continuously drying the film of coating composition so formed on the metal ribbon, said drying means including an oven supplied with heated air moving downwardly therethrough and guide means associated with said oven for moving the coated ribbon from the container for the coating composition upwardly through the oven, then for a short distance outside the oven, and then downwardly again inside the oven and then again out of the oven by a movement laterally therefrom at a point located a substantial distance above the lower end of the oven.

2. An apparatus for continuously coating a metal ribbon with a liquid coating composition which comprises a container for the liquid coating composition, means for guiding the metal ribbon into and out of the liquid in the container at a slow even speed, whereby to uniformly coat the metal ribbon with a thin smooth film of the coating composition, and means located adjacent the surface of said liquid in said container for providing the ribbon with an arcuate form transversely of its length as it leaves the body of coating composition in said container whereby to prevent vibration of the coated metal ribbon as it leaves said body.

3. An apparatus for continuously coating a metal ribbon with a liquid coating composition which comprises a container for the liquid coating composition, means for guiding the metal ribbon into and out of the liquid in the container at a slow even speed, whereby to uniformly coat the metal ribbon with a thin smooth film of the coating composition, and means for preventing vibration of the coated metal ribbon as it leaves the body of liquid coating composition in said container including means having a slot therein which slot is arcuate transversely of the line of

travel of said metal ribbon, through which slot the metal ribbon passes, the said means having the arcuate slot therein being located within said container for the coating composition a short distance below the upper surface of the coating composition in said container whereby the coated metal ribbon has a temporary arcuate form transversely of its length as it leaves the body of coating composition.

4. An apparatus as described in claim 3 further characterized in that the arcuate slot is formed between a pair of members having cooperating arcuate surfaces, one of said members being fixed and the other being yieldably pressed against said fixed member with sufficient force to give said coated metal ribbon said temporary arcuate form transversely of its length as it leaves the body of the coating composition.

5. An apparatus for continuously coating a metal ribbon with a liquid coating composition which comprises a container for the liquid coating composition, means for passing the metal ribbon through the liquid in said container at a slow even speed, whereby to uniformly coat the metal ribbon with a thin smooth film of the coating composition, said means for passing the metal ribbon including a roller driven at a slow even speed engaging the metal ribbon after the coating is applied and drawing the metal ribbon through the coating bath at said slow even speed and said means for passing the metal ribbon also including a supply reel and a second driven roller having a uniform peripheral speed slightly less than that of said first named roller and positioned at a place in the path of travel of said metal ribbon between said supply reel and said container, the metal ribbon being maintained in engagement with said second driven roller by means resiliently urging said metal ribbon against said second driven roller whereby the portion of metal ribbon extending between said second driven roller and said first driven roller is placed under tension.

6. An apparatus for continuously coating a metal ribbon with a liquid coating composition which comprises a container for the liquid coating composition, means for guiding the metal ribbon into and out of the liquid in the container at a slow even speed, whereby to uniformly coat the metal ribbon with a thin smooth film of the coating composition and means for preventing vibration of the coated metal ribbon as it leaves the body of liquid coating composition in said container including means having a slot therein which slot is arcuate transversely of the line of travel of said metal ribbon, through which slot the metal ribbon passes, the said means having the arcuate slot therein being located adjacent the upper surface of the coating composition in said container whereby the coated metal ribbon has a temporary arcuate form transversely of its length as it leaves the body of coating composition.

7. In a method of making short lengths of coated metal ribbon permanently set in an arcuate form transversely of their length the step which comprises first continuously coating a relatively long ribbon of the metal before subdividing said metal into lengths and before providing said permanent arcuate set, said coating being applied by continuously guiding the ribbon of the metal into and continuously drawing said ribbon vertically upwardly out of a body of liquid coating composition in a container at a slow even speed, providing said ribbon with an arcuate form

transversely of its length over a portion of its path of travel extending from a point a substantial distance within the body of liquid coating composition to a point a substantial distance beyond where said ribbon leaves the body of liquid coating composition and continuously drying the film of coating composition so formed on the long metal ribbon, said coating composition being maintained at uniform temperature and uniform composition during the coating operation.

8. A method for continuously coating a metal ribbon with a liquid coating composition which comprises guiding the metal ribbon into and drawing said ribbon vertically upwardly out of a body of the liquid coating composition at a slow even speed and providing the metal ribbon with an arcuate form transversely of its length over a portion of its path of travel extending from a point a substantial distance within the body of liquid coating composition to a point a substantial distance beyond where the metal ribbon leaves the body of liquid coating composition.

9. An apparatus for continuously coating a metal ribbon with a liquid coating composition which comprises a container for the liquid coating composition, means for maintaining the coating composition in said container at a uniform temperature throughout the coating operation, means for guiding the metal ribbon into and vertically upwardly out of the liquid in the container at a slow even speed, whereby to uniformly coat the metal ribbon with a thin smooth film of the coating composition and means for preventing vibration of the coated metal ribbon as it leaves the body of liquid coating composition in said container including means having a slot

therein which slot is arcuate transversely of the line of travel of said metal ribbon, through which slot the metal ribbon passes, the said means having the arcuate slot being located adjacent the upper surface of the coating composition in said container whereby the coated metal ribbon has a temporary arcuate form transversely of its length as it leaves the body of coating composition.

10. A method for continuously coating a metal ribbon with a liquid coating composition which comprises guiding the metal ribbon into and out of a body of liquid coating composition at a slow even speed and providing the metal ribbon with an arcuate form transversely of its length over a portion of its path of travel extending from a point a substantial distance within the body of liquid coating composition to a point a substantial distance beyond where the metal ribbon leaves the body of coating composition.

11. A method for continuously coating a metal ribbon with a liquid coating composition which comprises continuously guiding the metal ribbon into and drawing said ribbon vertically upwardly out of a body of the liquid coating composition in a container at a slow even speed, providing the metal ribbon with an arcuate form transversely of its length over a portion of its path of travel extending from a point a substantial distance within the body of liquid coating composition to a point a substantial distance beyond where the metal ribbon leaves the body of coating composition and continuously drying the film of coating composition so formed on the metal ribbon, said coating composition being maintained at uniform temperature during the coating operation.

GLENN L. SHERWOOD.
